CLAIM

The ornamental design for a handle for flatware, as shown and described.

DESCRIPTION

FIG. 1 is a right side elevational view of a handle for flatware showing our new design, the left side elevational view being a mirror image thereof;

FIG. 2 is a top plan view thereof;

FIG. 3 is a bottom plan view thereof;

FIG. 4 is a front elevational view, the rear elevational view being a mirror image thereof;

FIG. 5 is a right side elevational view of a second embodiment of our new design of FIGS. 1-4, the left side elevational view being a mirror image thereof;

FIG. 6 is a top plan view thereof;

FIG. 7 is a bottom plan view thereof; and,

FIG. 8 is a front elevational view, the rear elevational view being a mirror image thereof.

The broken lines showing a knife and fork in FIGS. 1 and 5, respectively, are environmental only and form no part of the claimed design.
